UNITED STATES PATENT OFFICE.

JAMES PAUL HOUK, OF MOUNTAIN GROVE, MISSOURI.

RAILWAY CROSSING.

Application filed January 24, 1923. Serial No. 614,712.

To all whom it may concern:

Be it known that I, JAMES PAUL HOUK, a citizen of the United States, and resident of Mountain Grove, in the county of Wright 5 and State of Missouri, have invented certain new and useful Improvements in Railway Crossings, of which the following is a specification.

My invention relates generally to railway 10 crossings, more particularly to railway crossings of the type embodying means for automatically rendering the track rails continuous for the passage of car wheels across the crossing, thereby obviating the jars, shocks 15 and wear which would be caused by the wheels when they cross a gap between intersecting rails, and it consists in the combinations, constructions and arrangements herein described and claimed.

20 An object of the invention is to provide an improved and simplified railway crossing of the character described which includes means adapted to be actuated by the first wheels of an approaching train to establish 25 and maintain continuity of rails for the passage of the train without any additional wear on the wheels of the train or on the elements of the railway crossing during the 30 passage of the train.

35 A further object of the invention is to provide a railway crossing of the character described which affords facilities for successively establishing and maintaining continuity of track rails for trains traveling 40 thereover in directions extending at right angles to each other.

45 A still further object of the invention is to provide a railway crossing of the character described which is strong and durable in construction, comprises but relatively few parts and which is not likely to wear out quickly in service.

50 Other objects and advantages will be apparent from the following description, considered in conjunction with the accompanying drawings, in which—

Figure 1 is a plan view showing a railway crossing embodying the invention,

55 Figure 2 is a similar view of a fragmentary portion of the structure shown in Figure 1, showing complete one of two complementary sections comprised in the crossing,

Figure 3 is a relatively enlarged plan view, showing a portion of one of the complementary sections of the crossing, portions

thereof being broken away to exhibit parts otherwise undisclosed, and

Figure 4 is a perspective group view showing in disassociated relation certain of the elements exhibited in the preceding views. 60

A railway crossing embodying the invention is adapted to join the rails 1—1 of a track generally designated A to the rails 2—2 of a track B, the joined together portions of the two tracks extending at right angles to each other. A railway crossing embodying the invention in the form now preferred by me includes two complementary sections indicated generally at C and C¹, 65 each of which is precisely identical in essential respects with the other. I shall therefore confine my description to the details of construction of the section C which will suffice also as a description of the details of construction of the section C¹ and have used 70 the same reference characters to designate like parts of the two sections.

The section C includes a flat base portion 75 which is of double cruciform shape and includes a longitudinal or straight body 4 80 provided at determined points along its length with pairs of oppositely extending lateral branches or arms 5—5 and 6—6 respectively, the branches or arms of each pair extending in alignment with each other 85 and at right angles to the body 4. The pairs of branches or arms 5—5 and 6—6 intersect the body 4 at appreciable and preferably equal distances from the opposite ends of the latter and are so located in respect to each 90 other that the distance therebetween is equal to the gauge or distance between the rails of one of the tracks with which the crossing is to be associated. In the embodiment of the invention illustrated the distance between 95 the pairs of branches or arms 5—5 and 6—6 is equal to the distance between the rails 2—2 of the track B, it being understood that such distances are computed between the longitudinal median lines of the 100 branches 5—5 and 6—6 and between the longitudinal median lines of the rails 2.

A track rail section 7 and a guard rail section 8 are formed integrally with the portion of the body 4 extending between the 105 respective pairs of branches and are upstanding from the latter. The track rail section 9 extending in upstanding relation to one of the branches 5 is integral with the latter and is merged at its inner end at a right angle 110

into a track section 10 which is upstanding from one end portion of the body 4 and is integral with the latter.

Track rail sections 11 and 12 similar to the 5 track rail sections 9 and 10 respectively are formed upon one of the branches 6 and the other end portion of the body 4. The said one branch 5 and the one branch 6 also have integral upstanding guard rail sections 13 10 and 14 respectively extending thereon in spaced parallel relation to the track rail sections 9 and 11 and along the proximate edges of the said one branch 5 and one branch 6. The guard rail sections 13 and 14 are outwardly flaring and thus extend toward each other adjacent to their outer ends. The second branch or arm 5 is formed with an integral upstanding track rail section 15 thereon, which track rail section is in axial 15 alignment with the track rail section 9. A track rail section 16 formed on the second branch 6 is in axial alignment with the track rail section 11. A guard rail section 17 formed on the second branch 5 is in axial 20 alignment with the guard rail section 13 and the guard rail section 18 on the second branch 6 is in axial alignment with the guard rail section 14. The end portions of the body 4 have integral guard rail sections 25 19 and 20 respectively which are in alignment with each other and with the intermediate guard rail section 8 and which flare laterally adjacent to their opposite ends as best seen in Figure 2.

30 The base 3 and the track and guard rail sections which have been described as being located thereon are formed by casting or in any other suitable manner in one piece and the track rail sections are preferably although not necessarily of the box type of construction, as shown. The integral track rail sections 9 and 10 are preferably of greater width for the greater part of their length than the width of the head flanges of 35 the rails 1-1 and 2-2 but are reduced or tapered at their outer ends as indicated at 9^a and 10^a respectively to conform in width to the head flanges of the track rails 2 and 1 to which the respective track rails sections 9 40 and 10 may be joined by nuts and bolts indicated generally at 21 or by any other suitable known connecting means. Track rail sections 11 and 12 are correspondingly reduced or tapered at their outer ends as indicated at 11^a and 12^a respectively and are joined respectively to one of the rails 2 and one of the rails 1 by splice plates and bolts 21. The intersecting portions of the branches 5-5 and the body 4 and of the branches 45 6-6 and body 4 are enlarged laterally as generally indicated at 22 and 23 respectively. The apex of the connected together track rail sections 9 and 10 terminates at the approximate center of the enlarged base portion 22 while the apex of the integral track

50 rail sections 11 and 12 terminates at a like point on the enlarged base portion 23.

The intermediate track rail section 7 terminates at its ends short of the inner ends of the track rail sections 10 and 12 and the track rail sections 15 and 16 likewise terminate short of the inner ends of the track rail sections 9 and 11 to provide clearance for the flanges of wheels passing from the track rail sections 10 or 12 to the intermediate track rail section 7 or vice versa or from the track rail sections 9 and 11 to the track rail sections 15 and 16 or vice versa. The guard rail section 8 likewise terminates at its end short of the inner end of the guard rail sections 19 and 20, the guard rail sections 13 and 17 terminate short of each other at their proximate ends and the guard rail sections 14 and 18 terminate short of each other at their inner ends. My invention provides means adapted to be actuated by the wheels of a train traversing the crossing to effect a bridging of the gap between adjacent aligned track and rail sections so that the passage of a train along either of the tracks A and B may be accomplished without excessive noise, shocks, jars or wear on the relatively moving parts. Such means includes pairs of cooperative bridge members 24 and 25 respectively movably supported upon each of the enlargements 22 and 23 and functioning in a manner to be hereinafter described.

55 It is to be observed at this point that the track rail section 15 tapers in width uniformly from a point adjacent to its outer to its inner end so that the distance between it and the guard rail 17 is greatest at the inner end of the latter. The track rail section 16 likewise tapers in width from a point adjacent to outer end to its inner end. The guard rail sections 17 and 18 terminate short of the corresponding ends of the track rail sections 15 and 16.

The intermediate track rail section 7 tapers uniformly in width from a point midway its length toward its opposite ends and diverges toward its opposite ends from the intermediate guard rail section 8. The intermediate track rail section 7 is of greater length than the guard rail section 8 and extends beyond the end of the latter. With this arrangement, a space is provided on each of the enlargements 22 and 23 for the accommodation of a pair of the cooperative bridge members 24 and 25.

60 Each of the bridge members 24 is substantially T-shaped and comprises a wedge shaped or tapering body 26 merged at its widest end into a head having portions 27 and 28 extending laterally of the body and in opposite directions. The body 26 is adapted to slide in contact with the tapering portion of one of the track rail sections 15 or 16 and to be complementary to such tapering portion. A stop element in the form of a

bolt 29 supported adjacent to its one end in a transverse opening through the tapered end portion of the track rail section 15 and at its other end in a transverse opening 5 through an upstanding lug 30 on the enlargement 22 coacts with an elongated opening 31 through the body 26 to limit the extent of movement of the body 26 in the direction of its length. A like stop element which is 10 also designated 29 and which is supported adjacent to one of its ends in a transverse opening in the inner end portion of the track rail section 16 and adjacent to its other end in an upstanding lug 32 on the 15 extension 23 coacts with the elongated opening or slot 31 in the body of the bridge member 24 which is disposed upon the enlargement 23.

It will be understood that the respective 20 bridge members 24 are slidably supported upon the base 3. Each bridge member 25 also is substantially T-shaped and includes a wedge-shaped or tapering body 33 merged at its widest end into a head having oppositely extending lateral branches 34 and 35 respectively. The tapering body 33 is adapted to slide upon the body portion 4 in contiguous relation to one of the tapering end portions of the section 7 and to complement 25 such tapering end portions. The lateral branch 28 of the bridge member 24 is reduced in thickness adjacent to its juncture with the body 26 by a notch 36 in the lower face thereof and a notch 37 30 in the upper face thereof to slidably engage a slot 38 in the lateral branch 35 of the associated bridge member 25 so that the cooperative members 24 and 25 on one of the enlargements 22 and 23 may be arranged 35 with the head portions thereof in intersecting relation, as shown. The notch 37 is of greater length than the width of the portion of the branch 35 extending therethrough so that limited movement of the bridge members 25 in the direction of the length of the 40 bodies 33 thereof is permitted. Bolts 39 constituting stop elements coact with elongated openings 40 in the bodies of the bridge member 25 to limit the extent of bodily movement of the bridge member 25 in the 45 direction of the length of the body thereof without causing any strain on the cooperative bridge member 24. One of the bolts 39 is supported adjacent to one of its ends 50 in an opening through one end portion of the track rail section 7 and adjacent to its other end in an opening through an upstanding lug 41 on the enlargement 22 while the other bolt 39 is supported adjacent to one 55 end in an opening through the other end portion of the track rail section 7 and adjacent to its other end in a lug 42 upstanding from the enlargement 23. The bolt 29 which constitutes the stop element for one of the 60 members 24 extends through an opening 43

in the lateral branch 35 of the cooperating member 25 and guides the latter in its bodily movement, being aided in such guiding action by a bolt 44 extending through an opening 45 in the other branch of the cooperating member 25. One of the bolts 44 is supported adjacent to its one end in a transverse opening through the track rail section 9 and adjacent to its other end in an opening through a lug 46 which is upstanding from the enlargement 22. The other bolt 44 is supported adjacent to one of its ends in an opening through the track rail section 11 and adjacent to its outer end in an upstanding lug 47 on the enlargement 23. 70 75 80

Each of the bolts 39 extends through an opening 48 in the lateral branch 28 of one of the bridge members 24 and aids a bolt 49 which extends through an opening 50 in the other lateral branch of the bridge member 24 in guiding the latter in its bodily movement in the direction of the length of the body thereof. One of the bolts 49 is supported adjacent to its one end in a transverse opening through one of the track rail sections 10 and adjacent to its other end in an opening through an upstanding lug 51 on the extension 22 while the other bolt 49 is supported adjacent to one of its ends in a transverse opening through the track rail section 12 and adjacent to its other end in an opening through an upstanding lug 52 on the enlargement 23. The length of the slot 38 is greater than the width of the portion of the branch 28 sliding therein so as to allow movement of each of the bridge members 24 in the direction of its length and relatively to the bridge member 25 with which associated. The upper wall of the slot 38 is cut away along one side of the body 33 as indicated at 53 to provide a gap for the accommodation of the flanges of wheels passing in one direction on the crossing. 90 95 100 105

From the foregoing description of the various parts of the device, the operation thereof may be readily understood. The bridge members 25 are spring pressed by expansion springs such as indicated at 54 in Figure 3 so that one of the members 25 is urged toward contiguous relation to the aligned body of the bridge member 24 at the track rail section 9 while the other bridge member 25 is urged toward contiguous relation to the body of the other bridge member 24 and the track rail section 11. An integral projection 55 on the head of one of the bridge members 24 is interposed between the head of the cooperating bridge member 25 and the proximate side of the track rail section 9 to hold the one bridge member 25 away from the track rail section 9. The projection 55 on the other bridge member 24 is interposed between the head of the other bridge member 25 and the track rail section 11 to hold 110 115 120 125 130

the second bridge member 25 away from the track rail section 11. At this time, the bridge members 24 are permitted to move in response to actuation by springs similar to the springs 54 and which are not shown in the drawings into contiguous relation to the aligned track rail section 10 and body of one of the members 25 and into contiguous relation to the track rail section 12 and the body 10 of the other bridge member 25. By means of splice plates and bolts indicated at 56 secured to the meeting ends of corresponding aligned track and guide rail sections, as illustrated in Figure 1, continuous rails are 15 provided for cars traversing the track B. The head of one of the bridge members 24 spans the gap between the ends of the guard rail sections 19 and 8 and the head of the other bridge member 24 spans the gap between 20 the other end of the guard rail section 8 and the guard rail section 20. The head of one of the bridge members 25 spans the gap between the guard rail sections 13 and 17 while the head of the other bridge member 25 spans the gap between the guard rail sections 14 and 18 so that a slot is provided 25 for the flanges of wheels traversing the track B. The passage of the train along the track B and on the crossing will thus be unattended by shocks, jars, undue wear on the relatively moving parts and will be practically noiseless.

The bridge members 24 and 25 will remain in position illustrated in Figures 1 and 2 30 until a train approaches on the track A. The first wheel of the train will contact with the beveled or inclined outer face of one of the branches of the bridge member 24 first encountered and will span the latter against 35 spring action from the position illustrated in Figures 1 and 2 away from the aligned rail track section 10 and body of the bridge member 25 or from the aligned body of the bridge member 25 and rail track section 12 40 against spring action. As soon as the contacted bridge member 24 has been moved a sufficient distance, the associated bridge member 25 will be permitted to move in response to actuation of the associated spring 45 54 until a projection 57 on the head thereof is interposed between the head of the bridge member 24 and one of the rail track sections 10 or 12, whereupon the bridge members 24 will be held away from the track rail section 50 55 with which associated. The head of each of the bridge members 25 has the branches thereof provided with beveled outer faces corresponding to the beveled outer faces of the branches of the head of each bridge member 24 so that the first wheel of a train approaching on the track B will engage with the beveled face of the proximate flange of one of the bridge members 25 and the latter will be moved from contiguous relation to 60 65 one of the track rail sections 9 or 11 to the

position illustrated in Figures 1 and 2. The projections 55 on the bridge members 24 will then function in the manner hereinbefore described to hold the bridge members 25 in open position until the bridge members 24 are operated by a train approaching on the track A.

It will thus be seen that the operation of the movable bridge members occasions but very little if any extra wear on the relatively moving parts of the crossing and of a train traversing the crossing for the reason that each bridge member will be positively held in open relation to the track rail when moved to such position by the first wheel of a train traversing the crossing until permitted to move to closed position to cause the operation of the bridge member associated therewith. As stated, each of the bridge members 24 and 25 is pressed toward closing relation to an adjacent track rail by an expansion spring, such as shown at 54 in Figure 3. Each expansion spring 54 reacts at one end against the bottom of a pocket formed in one of the track rail sections, such as the pocket designated 58 in Figure 3 while the other end of the spring engages a hook projection 59 on the body of the bridge member with which the spring is associated. Each of the bridge members 24 may have a second elongated opening through its body similar to the opening 31 and indicated at 60 in Figure 4. A bolt 61 connecting the track rail section 15 and the guard rail section 17 or the track rail section 16 and the guard rail section 18 coacts with the elongated opening 60 of one of the bridge members 25 to supplement the bolts 29 in limiting the longitudinal movement of the bridge member 24, thereby producing a strong and durable construction. In a like manner, bolts 62 connecting the track rail section 7 and the guard rail section 8 adjacent to the opposite ends thereof extend through elongated openings 63 in the bridge members 25 and supplement the bolts 39 in limiting longitudinal movement of the bridge members 25.

The bridge members 24 and 25 are shown as having grooves 54 in the lower faces of the heads thereof through which waste sand will move upon operative movement of the bridge members.

A lateral extension or enlargement 55 on the guard rail 17 contacts the stem of the bridge member 24 and holds it close to the rail section 15 during the movements of the bridge member. Sand waste grooves such as indicated at 54' may also be provided in the base portions 22 and 23.

Obviously, my invention is susceptible of embodiment in forms other than that illustrated herein and I therefore consider as my own all modifications and adaptations

of the forms of the device herein described which fairly fall within the scope of the appended claims.

Having thus described the invention, 5 what I claim is:—

1. A railway crossing of the character described comprising pairs of spaced apart rails lying in planes intersecting at right angles, each of said rails comprising fixed 10 aligned rail sections terminating short of each other at the intersection of the plane of said rail with the plane of one of the rails disposed at right angles thereto, a substantially T-shaped bridge member associated 15 with each of said rails, spring means acting on said bridge member continuously to urge the body of the latter into position to close the gap between adjacent ends of adjacent fixed sections of the rail and the 20 head of the bridge member against the intersecting rail, said head being adapted to be actuated by the flange of a car wheel traversing the intersecting rail and moved out of position to close the gap between said 25 fixed rail sections.

2. A railway crossing of the character described, comprising pairs of spaced apart rails lying in planes intersecting at right angles, each of said rails comprising fixed 30 aligned rail sections terminating short of each other at the intersection of the plane of said rail with the plane of one of the rails disposed at right angles thereto, a substantially T-shaped bridge member associated 35 with each of said rails, spring means acting on said bridge member continuously to urge the body of the latter into position to close the gap between adjacent ends of adjacent fixed sections of the rail, and the 40 head of the bridge member against the intersecting rail, said head being adapted to be actuated by the flange of a car wheel traversing the intersecting rail and moved out of position to close the gap between said 45 fixed rail sections, the head having grooves in the lower face thereof.

3. A railway crossing of the character described, comprising pairs of spaced apart rails lying in planes intersecting at right angles, each of said rails comprising fixed 50 aligned rail sections terminating short of each other at the intersection of the plane of said rail with the plane of one of the rails disposed at right angles thereto, a substantially T-shaped bridge member associated 55 with each of said rails, spring means acting on said bridge member continuously to urge the body of the latter into position to close the gap between adjacent ends of adjacent fixed sections of the rail, and the 60 head of the bridge member against the intersecting rail, said head having the outer faces of the branches thereof beveled and adapted to be engaged by the flange of a car 65 wheel traversing the intersecting rail to ef-

fect movement of the bridge member away from said intersecting rail.

4. A railway crossing of the character described, comprising pairs of spaced apart rails lying in planes intersecting at right angles, each of said rails comprising fixed aligned rail sections terminating short of each other at the intersection of the plane of said rail with the plane of one of the rails disposed at right angles thereto, a substantially T-shaped bridge member associated 70 with each of said rails, spring means acting on said bridge member continuously to urge the body of the latter into position to close the gap between adjacent ends of adjacent fixed sections of the rail, and the head of the bridge member against the intersecting rail, said head being adapted to be actuated by the flange of a car wheel traversing the intersecting rail and moved out of position to close the gap between said fixed rail sections, said bridge member having an elongated opening through the body thereof, and a stop member carried by one of the fixed 75 sections of the first rail and engaging the opening to limit the bodily movement of the bridge member.

5. A railway crossing of the character described, comprising pairs of spaced apart rails lying in planes intersecting at right angles, each of said rails comprising fixed aligned rail sections terminating short of each other at the intersection of the plane of said rail with the plane of one of the rails disposed at right angles thereto, a substantially T-shaped bridge member associated 80 with each of said rails, spring means acting on said bridge member continuously to urge the body of the latter into position to close the gap between adjacent ends of adjacent fixed sections of the rail, and the head of the bridge member against the intersecting rail, said head being adapted to be actuated by the flange of a car wheel traversing the intersecting rail and moved out of position to close the gap between said fixed rail sections, said bridge member having an elongated opening through the body thereof, and a stop member carried by one of the fixed 85 sections of the first rail and engaging the opening to limit the bodily movement of the bridge member.

6. A railway crossing of the character described, comprising pairs of spaced apart rails lying in planes intersecting at right angles, each of said rails comprising fixed aligned rail sections terminating short of each other at the intersection of the plane of said rail with the plane of one of the rails disposed at right angles thereto, a substantially T-shaped bridge member associated 90 with each of said rails, spring means acting on said bridge member continuously to urge the body of the latter into position to close the gap between adjacent ends of adjacent fixed sections of the rail, and the head of the bridge member against the intersecting rail, said head being adapted to be actuated by the flange of a car wheel traversing the intersecting rail and moved out of position to close the gap between said fixed rail sections, said bridge member having an elongated opening through the body thereof, and a stop member carried by one of the fixed 95 sections of the first rail and engaging the opening to limit the bodily movement of the bridge member.

7. A railway crossing of the character described, comprising pairs of spaced apart rails lying in planes intersecting at right angles, each of said rails comprising fixed aligned rail sections terminating short of each other at the intersection of the plane of said rail with the plane of one of the rails disposed at right angles thereto, a substantially T-shaped bridge member associated 100 with each of said rails, spring means acting on said bridge member continuously to urge the body of the latter into position to close the gap between adjacent ends of adjacent fixed sections of the rail, and the head of the bridge member against the intersecting rail, said head being adapted to be actuated by the flange of a car wheel traversing the intersecting rail and moved out of position to close the gap between said fixed rail sections, said bridge member having an elongated opening through the body thereof, and a stop member carried by one of the fixed 105 sections of the first rail and engaging the opening to limit the bodily movement of the bridge member.

8. A railway crossing of the character described, comprising pairs of spaced apart rails lying in planes intersecting at right angles, each of said rails comprising fixed aligned rail sections terminating short of each other at the intersection of the plane of said rail with the plane of one of the rails disposed at right angles thereto, a substantially T-shaped bridge member associated 110 with each of said rails, spring means acting on said bridge member continuously to urge the body of the latter into position to close the gap between adjacent ends of adjacent fixed sections of the rail, and the head of the bridge member against the intersecting rail, said head being adapted to be actuated by the flange of a car wheel traversing the intersecting rail and moved out of position to close the gap between said fixed rail sections, said bridge member having a notch in the upper side of one branch of the head thereof to accommodate the flange of a car 115 wheel traversing the said first rail.

9. A railway crossing of the character described, comprising pairs of spaced apart rails lying in planes intersecting at right angles, each of said rails comprising fixed aligned rail sections terminating short of each other at the intersection of the plane of said rail with the plane of one of the rails disposed at right angles thereto, a substantially T-shaped bridge member associated 120 with each of said rails, spring means acting on said bridge member continuously to urge the body of the latter into position to close the gap between adjacent ends of adjacent fixed sections of the rail, and the head of the bridge member against the intersecting rail, said head having the outer faces of the branches thereof beveled and adapted to be engaged by the flange of a car 125 wheel traversing the intersecting rail to effect movement of the bridge member away from said intersecting rail.

tersecting rail, said head being adapted to be actuated by the flange of a car wheel traversing the intersecting rail and moved out of position to close the gap between said 5 fixed rail sections, said bridge member having an elongated opening through the body thereof and a transverse opening through each branch of the head thereof, a stop element carried by a fixed section of the first 10 rail and engaging the elongated opening and guide means carried by a fixed section of the intersecting rail in sliding engagement with the transverse openings through the branches of the head of said bridge 15 member.

7. A railway crossing comprising two complementary sections, each of which is double cruciform in shape and includes spaced apart alined fixed sections of one rail of a track 20 and spaced apart alined fixed sections of the rails of a second track, the respective sections of each of said second named rails extending laterally of opposite sides of the first rail in planes intersecting at right angles the 25 plane of the latter, said sections of the first rail and of the second rails terminating at their adjacent ends short of juncture with one another, a pair of movable bridge members arranged at each intersection of the 30 plane of the first rail with the plane of one of said second rails, said bridge members having portions thereof in intersecting relation and being associated with fixed sections of rails lying in intersecting planes, spring 35 means urging each bridge into position to bridge the gap between adjacent ends of the fixed sections of the rail with which it is associated, means on each of said bridge members for engaging the other bridge member 40 to hold the second bridge member out of gap closing position when the first bridge member is in gap closing position, and means for connecting the meeting ends of the adjacent fixed sections of the second rails to 45 hold the crossing sections in complementary relation one to the other.

8. A railway crossing comprising two complementary sections, each of which is double cruciform in shape and includes spaced apart alined fixed sections of one rail of a track and spaced apart alined fixed sections of the rails of a second track, the respective sections of each of said second named rails extending laterally of opposite sides of the first rail in planes intersecting 50 at right angles the plane of the latter, said sections of the first rail and of the second rails terminating at their adjacent ends short of juncture with one another, a pair of movable bridge members arranged at each 55 intersection of the plane of the first rail with the plane of one of said second rails, each of said bridge members being substantially T-shaped and each having a body adapted to be slid along a fixed section of 60 one of said rails to and from position to close the gap between adjacent ends of the fixed sections of the rail with the head of the bridge member in abutting relation to the sides of adjacent sections of the rail lying in 65 a plane intersecting that of the first plane, the head portions of said bridge members being in intersecting relation in respect to each other and each having a notch in its upper side for the accommodation of the 70 flange of a car wheel traversing the rail with which associated, the outer faces of the head of each bridge member being beveled and adapted to be engaged by the flange of a car wheel and urged out of gap closing position 75 and each of said bridge members having a projection on the head thereof adapted to engage with the other bridge member when the former is in gap closing position and the latter is out of gap closing position to hold 80 the bridge members in the same relative position continuously, spring means urging each of said bridge members toward gap closing position, and means connecting the two sections of the crossing in position to 85 complement each other.

JAMES PAUL HOUK.
